UNITED STATES PATENT OFFICE.

JAMES W. LYONS, OF CHICAGO, AND JOHN B. SIEWERS, OF OAK PARK, ILLINOIS.

DESIGN FOR A RADIOCONSOLE.

Application filed August 28, 1924. Serial No. 10,571. Term of patent 14 years.

To all whom it may concern:

Be it known that we, JAMES W. LYONS and JOHN B. SIEWERS, citizens of the United States, residing at Chicago and Oak Park, respectively, in the county of Cook and State of Illinois, have invented a new and original Design for a Radioconsole, of which the following is a specification, reference being had to the accompanying drawing, forming part thereof.

Figure 1 is a perspective view of a console showing our new design; and

Figure 2 is a horizontal section thereof.

We claim:

The ornamental design for a radio console, as shown.

In witness whereof that we claim the foregoing as our invention, we have hereunto affixed our signatures, this 26th day of August, 1924.

JAMES W. LYONS.
JOHN B. SIEWERS.
